UNITED STATES PATENT OFFICE.

LEONARD LLEWELLYN LLANDAFF MATHEW, OF GLENCOE JUNCTION, NATAL, SOUTH AFRICA.

PLATFORM OR SKID PLATE FOR USE WITH LIGHT RAILWAYS, TRAMWAYS, AND THE LIKE.

Application filed April 19, 1923. Serial No. 633,194.

To all whom it may concern:

Be it known that I, LEONARD LLEWELLYN LLANDAFF MATHEW, a subject of the King of Great Britain, and resident of Glencoe Junction, Natal Province, Union of South Africa, have invented certain new and useful Improvements in Platforms or Skid Plates for Use with Light Railways, Tramways, and the like, of which the following 10 is a specification.

The present invention relates to skid plates or platforms of the kind used in connection with the tracks of light railways, tramways and the like in order to divert 15 a truck, coal-tub or other vehicle running on such tracks from one track to another or others at an angle thereto.

With skid plates, platforms or the like, as at present commonly constructed and 20 arranged, it is necessary when connecting the tracks or putting one track into communication with another or others laid at an angle thereto, to disconnect the rails of the one track and break the track for 25 a sufficient distance, or remove sufficient of the rails therefrom to permit of the skid plate or platform being placed in the space left between the ends of the rails of the broken track. With this form of skid plate the 30 vehicle passes off the ends of the rails on to the skid plate at a slightly lower level than the rails of the track, and is slewed or turned round to enable the vehicle to be run on to the other track. The breaking 35 of the first track is consequently necessary in all cases where it is desired to lay a second track at an angle to the first track.

The object of my invention is to construct a portable skid plate or platform 40 in such a way that when laying a track at an angle to an existing track, it is not necessary to break the existing track or disturb any of the rails thereof. It is also possible with my invention to transfer a 45 vehicle from the existing track without shock or jar to the vehicle and consequent breakage of the coal or other material being transported thereon.

In accordance with the invention the skid 50 plate or platform is adapted to be laid upon the rails of the existing track and to be detachably secured thereon in any desired position. It is fashioned with in-

clined extensions or portions which lie between the rails and are preferably provided with guard rails or plates so that the vehicle is guided up the inclined extension on to the top of the skid plate. The skid plate may be provided with a central 55 ring on which the vehicle is slewed or turned before it is run off on to the other track. The skid plate at the other side or sides is also constructed with downwardly inclined portions in which slots may be formed for retaining the ends of the rails 60 of the other track or tracks in position.

The invention will be further described with the aid of the accompanying drawings, wherein,

Fig. 1 is a plan view of the improved 70 skid plate.

Fig. 2 is a central half-sectional elevation of Fig. 1.

Fig. 3 is an end elevation of the skid plate.

Fig. 4 is a plan of a modified form of the 75 invention.

Fig. 5 is an end elevation of the construction shown in Fig. 4, and

Fig. 6 is a sectional detail view of line 80 x-x of Fig. 4.

Referring more particularly to the form of the invention illustrated in Figs. 1 to 3, 1 denotes the main portion of the skid plate or platform, and 2, 3 are the extensions formed at opposite sides or ends thereof, which are inclined upwardly from their outer ends to the level of the top of the main portion 1 of the skid plate. 4 represents the guard rails, shown of L section and riveted to the extensions 2, 3, at both 85 sides thereof and at such a distance apart that the flanges of the wheels of the vehicle will run at the outside of such guard rails 4 and up the inclined extensions 2, 3, on to the main portion 1 of the skid plate 90 or platform.

5, 6, are the rails of the existing track upon which the skid plate is placed and secured by means of wedges or the like 7 which are driven in between the webs of the existing 100 rails and angle iron pieces 8 riveted to the underside of the portion 1 of the skid plate in juxtaposition to the inner ends of the guard rails 4.

9 is the central guide ring which is fixed 105 on the top of the plate 1 and serves for guid-

ing the vehicle when it is slewed or turned round to run it on to the branch track at either side of the existing rails.

10, 11 are the downwardly inclined side portions of the skid plate or platform, and 12 are slots formed therein which engage with the webs of the rails 13 of the branch tracks between the head and base thereof. In this way the ends of the rails 13 of the other or branch tracks are retained at the required guage.

In the drawings I show the skid plate designed to be placed at a point in an existing track for diverting vehicles to another track 15 on each side of the existing track, or permitting the vehicles to be run over the skid plate on to the rails of the existing track at the opposite side thereof. It will be evident, however, that the skid plate can be constructed to receive the trucks from the end 20 of one track and transfer them to another track at an angle thereto.

In the modification illustrated in Figs. 4 to 6, the platform or skid plate is constructed 25 in such a form that it may, if desired, be shaped or pressed out of a single piece of sheet metal of the requisite dimensions. In this case the inclines 14, 15 are formed by the depression of the end portions 16, 17 of 30 the platform, so that the sides of the depressions engage with the inner sides of the rails of the track. In other respects this construction is the same as that described and illustrated in connection with Figs. 1 35 to 3.

What I claim as my invention and desire to protect by Letters Patent is:—

1. A device of the kind described, comprising a main portion adapted to be placed 40 upon the rails of the track, said main portion being fashioned with an extension which is adapted to fit between the rails of the track and is inclined upwardly from the outer end, up which incline the truck is run on to the main portion, the main portion being fashioned at an adjacent side with a downwardly inclined portion down which the vehicle is run on to the lines of the branch track, and means including wedges for fixing 45 the main portion in position on the track, as set forth.

2. A device of the kind described, comprising a main portion adapted to be placed 55 upon the rails of the track, said main portion being fashioned with an extension which is adapted to fit between the rails of the track and is inclined upwardly from the outer end, up which incline the truck is run on to the main portion, the main portion being fashioned at an adjacent side with a downwardly inclined portion down which 60

the vehicle is run on to the lines of the branch track, and means including members fixed to the underside of the main portion near the rails and wedges positioned between said members and the rails for fixing the main portion in position on the track, as set forth.

3. A device of the kind described, comprising a main portion adapted to be placed 65 upon the rails of the track, said main portion being fashioned with an extension which is adapted to fit between the rails of the track and is inclined upwardly from the outer end, up which incline the truck is run on to the main portion, the main portion being fashioned at an adjacent side with a downwardly inclined portion down which the vehicle is run on to the lines of the branch track, means including wedges for 70 fixing the main portion in position on the track, and guides fixed to the opposite sides of the inclined extension, as set forth.

4. A device of the kind described, comprising a main portion adapted to be placed 75 upon the rails of the track, said main portion being fashioned with an extension which is adapted to fit between the rails of the track and is inclined upwardly from the outer end, up which incline the truck is run on to the main portion, the main portion being fashioned at an adjacent side with a downwardly inclined portion down which the vehicle is run on to the lines of the branch track, and means including wedges 80 for fixing the main portion in position on the track, and the downwardly inclined portion being constructed with slots into which project the rails of the branch track, as set forth.

5. A device of the kind described, comprising a main portion adapted to be placed 85 upon the rails of the track, said main portion being fashioned at two opposite sides with an extension which is adapted to fit 90 between the rails of the track and is inclined upwardly from the outer end, up which incline the truck is run on to the main portion, the main portion being fashioned at the two other sides with a downwardly inclined 95 portion down which the vehicle is run on to the lines of the branch track, and means including wedges for fixing the main portion in position on the track, as set forth.

In testimony whereof I have signed my 105 name to this specification in the presence of two subscribing witnesses.

LEONARD LLEWELLYN LLANDAFF MATHEW.
